(57) **CLAIM**

I claim the ornamental design for a seat, as shown and described.

DESCRIPTION

FIG. 1 is a front view of one embodiment of my new seat design in the form of a sofa.

FIG. 2 is a side view of this embodiment of the seat.

FIG. 3 is a perspective view of this embodiment of the seat.

FIG. 4 is a rear view of this embodiment of the seat.

FIG. 5 is a side view of this embodiment of the seat.

FIG. 6 is a top view of this embodiment of the seat.

FIG. 7 is a front view of a further embodiment of my new seat design in the form of a chair.

FIG. 8 is a side view of this further embodiment of the seat.

FIG. 9 is a perspective view of this further embodiment of the seat.

FIG. 10 is a rear view of this further embodiment of the seat.

FIG. 11 is a side view of this further embodiment of the seat; and,

FIG. 12 is a top view of this further embodiment of the seat.

As shown in the drawings herein, broken (dotted) lines are used to indicate stitching.
